CLAIM

The ornamental design for a food container lid, as shown and described.

DESCRIPTION

FIG. 1 is a top, left-side perspective view of a food container lid showing my new design according to a first embodiment. FIG. 2 is a front view of my new design shown in FIG. 1. FIG. 3 is a left-side view of my new design shown in FIG. 1.

FIG. 4 is a cross-sectional view of my new design shown in FIG. 1 along cross-section line 4-4 of FIG. 3.

FIG. 5 is a front, top perspective view of a food container lid showing my new design according to a second embodiment. FIG. 6 is a front view of my new design shown in FIG. 5. FIG. 7 is a right-side view of my new design shown in FIG. 5.

FIG. 8 is a top view of my new design shown in FIG. 5. FIG. 9 is a cross-sectional view of my new design shown in FIG. 5 along cross-section line 9-9 of FIG. 8; and, FIG. 10 is a cross-sectional view of my new design shown in FIG. 5 along cross-section line 10-10 of FIG. 8. The portions of the food container lid shown in short broken lines form no part of the claimed design.
